UNITED STATES PATENT OFFICE.

CHARLES E. DATH, OF CHICAGO, ILLINOIS, ASSIGNOR TO WILLIAM H. MINER, OF CHAZY, NEW YORK.

ANTIFRICTION BEARING.

Application filed December 27, 1921. Serial No. 525,110.

To all whom it may concern:

Be it known that I, CHARLES E. DATH, a citizen of the United States, residing at Chicago, in the county of Cook and State of Illinois, have invented a certain new and useful Improvement in Antifriction Bearings, of which the following is a full, clear, concise, and exact description, reference being had to the accompanying drawings, 10 forming a part of this specification.

This invention relates to improvements in anti-friction bearings.

In the manufacture, shipping and application of anti-friction bearings, particularly 15 anti-friction bearings employed as side bearings on railway cars, it is highly essential that the entire device be shipped completely assembled without possibility of any of the parts becoming lost or disarranged either 20 accidentally or from deliberate tampering. Many expedients have heretofore been suggested for permanently retaining the parts of side bearings in assembled relation, but many of the same have not proved entirely 25 satisfactory due to either the expense of applying such retaining means or the difficulty in always applying the same properly, due to the variations which necessarily occur in the manufacture of the parts, most of 30 which are in the form of castings.

The object of my invention is to provide a simple, effective and relatively inexpensive means for retaining the parts of an anti-friction bearing in assembled relation and more 35 particularly as applied to a side bearing for railway cars.

In the drawing forming a part of this specification, Figure 1 is a vertical sectional view taken parallel to the length of a car 40 through the ends of the body and truck bolsters and showing my improvements in connection therewith. Fig. 2 is a vertical sectional view corresponding substantially to the broken section line 2-2 of Figure 1. 45 And Fig. 3 is a detail perspective of one of the retaining studs prior to its application to the other parts of the side bearing.

In said drawing, 10 indicates the under 50 side of a body bolster of a car and 11 the upper side of an opposed truck bolster. In the instance shown, the improved side bearing is applied to the truck bolster and the same comprises, broadly, a housing, base casting or retaining member designated 55 generally by the reference A; a wear or bear-

ing plate B; a rolling anti-friction element proper C; and special means for retaining the parts assembled hereinafter specifically described.

The retaining member or base casting A, 60 as shown, is formed with a bottom wall 12, vertically extending spaced side walls 13-13, vertically extending end walls 14-14, reinforcing and limiting ribs 15-15 on the interior of the casting at the ends thereof, 65 and corner lugs or ears 16-16 by which the casting is adapted to be riveted or otherwise rigidly secured to the truck bolster.

On its interior, the base casting A, in the bottom thereof, is preferably provided with 70 a pair of upstanding knobs or teeth 17-17, which extend through correspondingly located openings or perforations 18-18 in the preferably hardened wear plate B. The thickness of the wear plate B is less than the height of the teeth 17, so that portions of the latter project upwardly and are adapted to engage in corresponding openings 19-19 provided in the bottom of the anti-friction element C to thereby prevent the latter from 75 being shifted bodily with respect to the base casting A.

The anti-friction element proper C, in the form shown, is of the rolling rocker gravity self-centering type and is preferably formed with top and bottom concentric bearing surfaces 20 and 21, the latter being of longer radius than the former. Said top and bottom bearing surfaces 20 and 21 are merged with arcuate side surfaces 22-22. With 80 the arrangement shown, it is evident that, when the element C is shifted to either side of its normal central position shown in Figure 1, the center of mass is elevated and consequently the element will automatically 85 return to central position upon removal of the actuating force.

To retain the element C permanently within the base casting A, which, in turn, will retain the wearing plate B in position, I 90 employ the following means. The rocker element C, when cast, is formed with recesses 23-23 on each end thereof in axial alignment. Each of said recesses 23, at its inner end, is flared toward the center of the rocker, 95 as indicated at 23^a and projecting within the flared recess at its inner end is a cone-shaped lug 24 integral with the body of the rocker element C.

The side walls 13 of the base casting are 110

provided with upwardly curved arcuate elongated openings 25 opposite the openings 23 of the element C. The vertical height or width of the openings 25 is made slightly greater than the diameter of the openings 23 so as to readily permit insertion of the retaining tubular studs D therethrough. 5 Each of the studs D, shown in detail in Figure 3, preferably consists of a section of pipe of suitable diameter and material so that the cost thereof is kept at a minimum. One end of each of the tubular studs D is provided with a plurality of longitudinally extending cuts 26-26 which may be conveniently formed by sawing, thereby leaving a plurality of tangs 27-27. The tubular studs D, in the condition shown in Figure 3 and above described, are then passed through the respective openings 25 of the base casting 10 A and driven into the openings 23 of the rocker element C, and, on account of the elasticity of the metal comprising the studs D and the peculiar formation within the rocker element C, the tangs 27 will be flared or expanded so as to fit snugly within the inwardly flaring portions 23a of the openings of the rocker element C. In this manner, the following studs D are permanently (for all practical purposes) attached to the 15 rocker element C and by leaving a portion of the studs D extending within or through the openings 25 of the base casting, the rocker element C cannot thereafter be detached from the base casting, although allowed full freedom in rolling back and forth.

The arrangement shown is inexpensive both with respect to the cost of the material and parts and also with respect to the labor in assembling the parts.

40 I claim:

1. In an anti-friction bearing, the combination with a retaining member having a longitudinally extending bearing surface and spaced side walls; of a cast metal anti-friction element adapted to roll back and forth on said bearing surface and between said side walls; and means for retaining said element in assembled relation with said retaining member comprising stud members at each end of the anti-friction element and projecting therefrom within corresponding, elongated slots in the side walls to allow said stud members to work back and forth therein, said stud members being formed of metal

each of said stud members having its inner end extending and expanded within a corresponding opening in the anti-friction element to thereby prevent its withdrawal therefrom. 55

2. In an anti-friction bearing, the combination with a retaining member having a longitudinally extending bearing surface and spaced side walls; of an anti-friction element adapted to roll back and forth on said bearing surface and between said side walls, 60 said anti-friction element being formed of metal and provided with inwardly flaring openings at opposite sides and integral raised portions at the inner ends of said openings; and means for retaining said element in assembled relation with said retaining member comprising tubular stud members at each end of the anti-friction element, 65 each of said stud members having its inner end extended within a corresponding opening of the anti-friction element and expanded within the flaring portion thereof to rigidly attach the same to said element, the other ends of said stud members projecting beyond the ends of the anti-friction element, 70 the side walls of the base casting having openings therein within which said extended ends are adapted to move back and forth. 75

3. As an article of manufacture, an anti-friction element for side bearings, comprising a cast metal body provided with alined inwardly flaring openings at opposite sides having raised portions at the inner ends thereof, said raised portions being cast integral with said body, and oppositely projecting hollow trunnions fixedly secured to said body by having their inner ends split and expanded in said flaring openings. 85

4. As an article of manufacture, a cast metal anti-friction element for side bearings 90 provided with inwardly flaring trunnion receiving openings at opposite sides thereof, and conical raised portions at the inner ends of said openings, said raised portions being cast integral with said element. 95

In witness that I claim the foregoing I have hereunto subscribed my name this 9th day of Dec., 1921. 100

CHARLES E. DATH.
